UNITED STATES PATENT OFFICE

2,418,126

STAPLE FIBER OPENER

John E. Spalding, Nitro, and Dan B. Wicker, Dunbar, W. Va., assignors to American Viscose Corporation, Wilmington, Del., a corporation of Delaware

Application July 17, 1943, Serial No. 495,226

3 Claims. (Cl. 68—205)

1

This invention relates to devices for wet-opening clumps of fibers, such as cotton, wool and rayon staple.

It is an object of this invention to provide for the transferring of the fiber clumps through a pool, or preferably in succession through a series of pools, of liquid, such as water, formed in an inclined trough, in which pool or pools the fibers are temporarily retained submerged and subjected to a controlled, gentle agitation and from which they are removed by entrainment. A particular object of this invention is to so construct and arrange the wet-opening device as to assure the maintenance of the capacity of the liquid pool or pools and to prevent the accumulation of the fibers within the pool or pools or therebetween, thus assuring efficient and uniform opening action over long periods of time. These and other objects and advantages of the invention will be apparent from the drawing and the description thereof.

In the drawing, illustrative of the invention,

Figure 1 is a cross-sectional elevation of one embodiment of the invention,

Figure 2 is a plan view of the device of Figure 1,

Figure 3 is an elevation showing another embodiment of the invention, and

Figure 4 is a plan view of the device of Figure 3.

In accordance with the invention, the fiber clumps and a liquid are delivered to the top of a chute or trough, the liquid-carrying bottom of which is inclined at an angle between 5° and 85° and preferably between about 30° and about 60° to the horizontal. An inclination of about 45° is ordinarily best where such an angle can be accommodated. The bottom of the trough is provided with at least one baffle but preferably with a series of transverse baffles or partitions which are preferably spaced along the trough at such distances apart that the fiber-containing liquid falling over the top of any one of the baffles will impinge upon the bottom of the trough in advance of or above the body of the liquid pool formed back of the next baffle so that excessive splashing and irregular transference of the fibers over the baffles are avoided. This distance between baffles, where a plurality thereof is used, may be varied widely but is preferably such that

2

the condition just mentioned is met. This preferred minimum limiting distance is shorter, the less steep the inclination of the trough. Where a single baffle is used, it may advantageously be disposed at or near the discharge end of the chute.

The up-stream face of the baffles may be set at right angles to the bottom of the trough or it may be set at less abrupt an angle thereto to streamline the flow, the latter arrangement being preferable where the inclination of the trough is at a lower angle up to about 30° to the horizontal. The downstream side of the baffles may also be sloped gently to the trough bottom rather than at right angles thereto if desired. Additional liquid may be, and preferably is, supplied to the bottom of the liquid pool or pools to assist the agitation thereof, to assist the regular propulsion of the fiber-containing liquid over the baffle, and to assure that the fibers are only temporarily retained in the pool by preventing their accumulation therein.

Referring to Figures 1 and 2 which show one embodiment of the fiber opening device of this invention, there is shown a belt conveyor 2 which may receive the fibers directly from a rayon staple fiber cutter or from any suitable source of natural or artificial fibers of non-continuous lengths. The fibers fall from the conveyor 2 into the top of the trough 3 having the inclined bottom 4 and baffles 5, 6 and 7. Any number of baffles may be used. They may be of the same shape, though each baffle as shown is of a different shape to illustrate some of the various shapes that may be used. While the baffles are shown equidistantly spaced, they may as well be irregularly spaced provided they are spaced at least a sufficient distance so that the fiber-containing liquid falling over the tops of baffles 5 and 6 strike the bottom 4 of the trough above the level of the pools formed back of the baffles 6 and 7 respectively.

The transfer of the fibers from the conveyor 2 to the trough 3 may be assisted by the washing action of a liquid spray from fan-shaped nozzles 8 which plays downwardly upon the top of the overrunning belt portion and by the action of a liquid spray from fan-shaped nozzles 9 directed upwardly to graze and play upon the underside of the belt 2. A plurality of fan-shaped nozzles 10

provide a sheet or film of the liquid from the top of the trough and auxiliary spray nozzles 11 are shown above the trough. The bottom of the trough is provided with a row of approximately horizontal passages 12 just above each baffle but well below the liquid level in the pool backed up thereby. These passages communicate by pipes 13 with a header to which the liquid is forced by a suitable pump (not shown). The liquid forced into the pools near their bottoms through the passages 12 assists in preventing accumulation of fibers in the corner formed between the baffles 5, 6 and 7 and the inclined bottom 4 of the trough, assists the gentle agitation of the fiber-containing liquid in the pools, and helps to provide uniform and dependable propulsion of the liquid suspension fibers over the tops of the baffles.

Figures 3 and 4 show an adaptation of the invention for service in direct combination with a form of staple fiber cutter of the type disclosed in Beria Patent No. 1,723,998. The continuous filamentary tow is fed downwardly into the axial bore 14 in the rotating cutter disk 15. This disk is provided with a radial channel terminating in the opening 16 from which the end of the tow to be cut projects. Two stationary knives 17 are positioned at opposite sides of the cutter disk and the inclined troughs 18 are positioned near the knives so that the fiber clump cut by each of the knives is received by the corresponding trough. The troughs are provided with baffles 19 spaced apart as described above. Fan-shaped spray nozzles 20 are arranged to play upon the top of the troughs to form a sheet or film of liquid flowing over the bottoms thereof. These nozzles may be supplied from a common header 21 which may also, if desired, feed a certain amount of the liquid through pipe 23 into the mouth 14 of the cutter disk to lubricate the knives. Plates 22 arranged on the sides of the troughs back of the knives serve to deflect back into the trough any liquid or wet fibers splashed from the bottom of the trough by virtue of the high velocity of impact thereof against the trough bottom.

Any liquid at any temperature may be utilized for wet-opening provided such liquid has no deleterious action upon the fibrous material being treated. For freshly spun viscose staple, treatment with water at any temperature may be resorted to, but the most effective treatment seems to be obtained with water as temperatures of 45° C. or higher. The wet opening may be performed on the staple at stages where it is susceptible to the development of crimp when thus treated. If desired, the wet-opening liquid may be a processing liquid. For example, cut staple of cellulose xanthate may be regenerated and opened simultaneously with the same liquid. Again, a cut viscose staple may be desulfurized and opened in the same liquid. Similar combination of the opening and the processing of other artificial or even natural fibers may be applied in accordance with the present invention.

Wet opening of artificial staple fibers, such as of viscose rayon, in accordance with this invention results in a staple fiber product which exhibits somewhat more crimp or curl, greater cohesion during drafting to yarns, and generally improved textile processing characteristics. It may advantageously be applied to cut staple prior to liquid treatment, in which case it renders the staple more susceptible to uniform penetration and processing by the liquids, and the subsequent drying is more uniform and rapid.

The wet opening process of the present inven-

tion relies solely upon hydraulic action to effect transfer of the fibers into and out of a given pool, to effect controlled agitation therein to prevent accumulation of fibers and clogging of the chute, and to provide for uniform and dependable propulsion of the fibers through the pool. By avoiding mechanical action, filament tangling and breakage are substantially eliminated and economies are effected in equipment, operation thereof, and maintenance thereof.

10

It is to be understood that changes and variations may be made without departing from the spirit and scope of the invention as defined by the appended claims.

15 We claim:

1. In a device for the treatment of fibers, a chute having an imperforate liquid-carrying bottom surface inclined to the horizontal, at least one transverse baffle in the chute projecting from its bottom and extending substantially horizontally across the entire width of the chute, means for delivering fibers and introducing a liquid into the upper end of the chute whereby the fibers are suspended and carried in suspension over the bottom surface of the chute to at least one pool retained by a respective baffle, and hydraulic means for gently agitating the fibers suspended in the pool and for removing the fibers from the pool, said hydraulic means comprising a generally horizontal row of openings in the chute bottom above the baffle and means for forcing additional liquid through the openings into the chute comprising passages through the chute bottom communicating with the openings and arranged to direct the additional liquid toward the baffle.

2. In a device for the treatment of fibers, a chute having an imperforate liquid-carrying bottom surface inclined to the horizontal, a plurality of transverse baffles in the chute each projecting from its bottom and extending substantially horizontally across the entire width of the chute, means for delivering fibers and introducing a liquid into the upper end of the chute whereby the fibers are carried in suspension over the bottom surface of the chute successively through pools retained by the several baffles and hydraulic means for gently agitating the fibers in the pools and for preventing accumulation therein, said hydraulic means comprising a generally horizontal row of openings in the chute bottom above each of the baffles below the surface of the pool retained thereby and means for forcing additional liquid through the openings into the chute comprising passages through the chute bottom communicating with the openings and arranged to direct the additional liquid toward the baffles.

3. In a device for the handling of fibers, a chute having an imperforate liquid-carrying bottom surface inclined between 5° and 85° to the horizontal, a plurality of transverse baffles in the chute each projecting from its bottom and extending substantially horizontally across the entire width of the chute, means for delivering fibers to the upper end of the chute, means for introducing a liquid into the upper end of the chute whereby the fibers are carried in suspension over the bottom surface of the chute successively through pools retained by the several baffles, said baffles being spaced at least a sufficient distance apart so that the liquid suspension falling over each baffle except the last impinges against the chute bottom above the pool retained by the next baffle in advance thereof, said hydraulic means comprising a generally horizontal row of openings in the chute bottom above each of the baffles
